UNITED STATES PATENT OFFICE

119,836

DESIGN FOR A PIN CLIP

Joseph Wuyts, New York, N. Y.

Application February 21, 1940, Serial No. 90,419

Term of patent 3½ years

To all whom it may concern:

Be it known that I, Joseph Wuyts, a citizen of the United States of America, residing in the city of New York, county of New York, and State of New York, have invented a new, original, and ornamental Design for a Pin Clip, of which the following is a specification, reference being had to the accompanying drawing, forming part thereof.

Fig. 1 is a plan view of a pin clip showing my new design.

Fig. 2 is an edge view thereof.

I claim:

The ornamental design for a pin clip, substantially as shown.

JOSEPH WUYTS.
